UNITED STATES PATENT OFFICE.

JOHN T. HOWIESON, OF NEW YORK, N. Y., ASSIGNOR OF ONE-HALF TO
FRANK SPIEKERMAN, OF PHILADELPHIA, PENNSYLVANIA.

CALCULATING-MACHINE.

SPECIFICATION forming part of Letters Patent No. 712,381, dated October 28, 1902.

Application filed December 20, 1901. Serial No. 86,899. (No model.)

To all whom it may concern:

Be it known that I, JOHN T. HOWIESON, a citizen of the United States, residing at New York, in the county of New York, State of New York, have invented certain new and useful Improvements in Calculating-Machines, of which the following is a description, reference being had to the accompanying drawings and to the figures of reference marked thereon.

My invention relates to calculating devices and is especially designed and intended to be used in connection with or as an attachment to a type-writing machine, though it embodies features of construction and combination of elements applicable to key-operated calculating-machines generally and is capable of use separate from a type-writing machine. As an attachment for type-writing machines it comprises a device adapted to be readily connected to the frame of a type-writing machine and carrying calculating mechanism adapted to be operated by the numeral-keys only when the paper-carriage has reached a predetermined point in its travel, the numeral-keys being capable of operation at any time during the travel of the paper-carriage other than a particular predetermined series of spaces without effecting operation of the calculating mechanism. The fact that except at the predetermined point in the movement of the carriage the numeral-keys, if operated, do not effect movement of the calculating mechanism is of particular importance, as in the form of keyboard commonly used the type-bar operated by each key carries two characters, the type-bars operated by the numeral-keys from "2" to "9" commonly carrying punctuation marks, as well as a numeral, and the "1" and "0" being the lower-case "l" and the upper-case "O," respectively, so that it is necessary that these keys be capable of operation without effecting the movement of the calculating mechanism, except while the machine is printing the numbers which it is desired should form the basis of the calculation.

The device further comprises mechanism by which in writing numbers commas may be printed at proper places to point off and in writing numbers representing dollars and

cents or other denominations periods or other marks may be printed at proper places without effecting the accuracy of the calculation made by the device.

55

Special features of construction of my invention permit by a slight adjustment the printing of entire lines without the operation of the calculating mechanism and also permit the calculating mechanism to be readily disconnected from the key-levers of the machine.

The device is primarily intended to add numbers as they are written in column by the machine and to show the total of the numbers so written directly in front of the operator; but it is so constructed as to be capable of use also for subtraction, as well as for multiplication and division.

With these objects in view and without limitation of the invention to calculating devices for use in connection with or as attachments to type-writing machines my invention consists in the construction and combination of elements hereinafter particularly 75 pointed out in the claims.

Referring to the drawings, Figure 1 is a perspective view showing the calculating device applied to a type-writing machine of the ordinary type. Fig. 2 is a perspective view showing, on an enlarged scale, the attachment carried by the paper-carriage by which the registering devices are thrown into position to be operated. Fig. 3 is a front view of the operating mechanism, the front plate of the machine and the connection with the type-writer keys being removed. Fig. 4 is a rear view of the machine, part of the mechanism being removed. Fig. 5 is a perspective view showing the tripping devices detached. Fig. 6 is a front view of the machine. Fig. 7 is an end view of the machine. Fig. 8 is a cross-sectional view, on an enlarged scale, showing the tripping devices and their connection with the actuating mechanism for the registering-wheels. Fig. 9 is a cross-sectional view showing the operating-lever and its connections, looking toward the left end of the machine. Figs. 10 and 11 are cross-sectional views showing the actuating devices for the registering-wheels at the different points in their operation looking toward the left of the

machine. Figs. 12 and 13 are similar views looking toward the right of the machine. Fig. 14 is a front view with part of the mechanism removed, showing the stop-arms and 5 the means for operating them. Fig. 15 shows a plan and end view of the pawl 53. Fig. 16 shows similar views of the pawl-carrier 51. Fig. 17 is a cross-sectional view of the bearing-piece on which the devices for actuating 10 the registering-wheels are carried. Fig. 18 shows a side and end view of the cam-plate 55. Fig. 19 shows a side and end view of the pawl-carrier 52. Fig. 20 shows in section the manner in which the operating-lever is carried 15. Fig. 21 shows in cross-section the lever which carries the locking-bail. Fig. 22 is a sectional view showing, on an enlarged scale, the bearing-piece 50 and the devices carried by it. Fig. 23 is a front view showing the 20 full-stroke mechanism. Fig. 24 is a sectional view showing the same mechanism. Fig. 25 is a front view showing the registering-wheels and carrying mechanism. Figs. 26 and 27 are cross-sectional views showing the connections 25 for operating the registering-wheel of higher denomination in the operation of carrying. Fig. 28 is a front view of the cam-plate 55 and the connection for lifting the carrying-pawls. Fig. 29 shows in cross-section 30 and plan view the collar connecting the shaft 27 with the shaft 15. Fig. 30 shows in cross-section and plan the double arm-carrying pawl. Fig. 31 shows in side view and cross-section one of the registering-wheels with its 35 attachments. Fig. 32 shows in side and front view the detent-pawl. Fig. 33 shows in side and front view the upwardly-extending arm carried by the guide-plate 85. Fig. 34 is a sectional view similar to Fig. 22, but extended 40 to show a complete group of the devices carried on the sleeve 11. Fig. 35 is a plan view of the guide-plate, and Fig. 36 is a detail view showing the segmental rack and its connections. 45 Referring to the drawings, 1 indicates the frame of a type-writing machine of the type commonly in use, known as the "Remington type," having a keyboard 2, of the type commonly known as the "universal keyboard," 50 having the numeral-keys "2" to "9," inclusive, arranged in the rearmost row and having the "L" key (the lower-case "l" being used for the numeral "1") in the second row and the "O" key (the upper-case "O" being 55 used as the numeral "0") in the third row. 3 indicates the paper-carriage of the type-writing machine.

Directly above and in rear of the keyboard and secured, preferably, to the top plate 4 of the frame are the end plates 5 of the calculating devices. For convenience in attaching them to the top plate these end plates may have their ends bent over, as shown at 5'. These end plates are connected by the rods 6; and shafts hereinafter referred to and support the working parts of the device which embodies my invention. A front plate 6,

preferably made in two parts 6' and 6", extends from one of these end plates to the other and is removably secured thereto in any convenient manner. 70

Journaled in the end plates 5 is a main shaft 7. Preferably at one end the main shaft is provided with a spring 8, (shown in Fig. 4,) by which it is returned to normal position 75 after it has been rocked on its bearings in the manner and for the purpose hereinafter described.

Carried by the main shaft 7 are a number of radial arms 9, all in the same plane and 80 all of substantially the same length. These radial arms 9, as hereinafter described, form an essential part of the mechanism by which the registering-wheels are operated. These radial arms are preferably made slightly adjustable, being carried for this purpose in holes drilled in the main shaft 7, as shown in Fig. 8, and are held in adjusted position by means of set-screws 10. 85

Surrounding the main shaft and concentric therewith, but not in contact therewith, is a stationary sleeve 11, the ends of which rest in circular recesses 12 in the end plates 5. This sleeve is provided with a series of slots 13, corresponding in number and position to the 95 radial arms 9 and of sufficient length to permit the movement of these arms which they must have to effect their function of moving the actuating devices for the registering-wheels. The sleeve 11 is also provided with 100 a series of openings 14 to permit access to the set-screws 10. On this sleeve 11 are supported, so as to rock freely thereon, the actuating devices by which movement is transmitted to the radial arms 9 and by which the 105 movement of these radial arms is transmitted to the registering-wheels. 110

15 is a shaft or rod supported by the end plates 5 and carrying the registering-wheels 16. These registering-wheels are supported 115 by and turn freely on the rod 15 and are each provided with a pinion 16'. The rod 15 is not intended to rotate upon its axis, except as hereinafter described for the purpose of resetting the registering-wheels to zero, as herein- 120 after described.

To the rear of and preferably slightly above the plane of the rod 15 is a stationary rod 17, which serves to support and form a bearing for tripping devices 18, by which at a predetermined point in the movement of the paper-carriage the actuating mechanism of one of the registering-wheels 16 is brought into position to be operated by the operation of any one of the numeral-keys of the machine. 125 These tripping devices comprise an upper portion 19, extending forward immediately below the top plate 4 of the type-writing machine in position to be struck and forced backward by a device carried by the paper-carriage, a vertical portion 20, a rearwardly-extending horizontal portion 21, a sleeve 22 carried on the rod 17 and adapted to rock on said rod in the ordinary operation of the 130

mechanism and to be shifted longitudinally of the rod when desired. Each of the sleeves 22 carries a rearwardly-projecting pin 22', by which the sleeve may be shifted longitudinally, as hereinafter described. The tripping mechanism also includes a downwardly-extending arm 23, carried by the rod 17 and arranged to be rocked thereon with the sleeve 22, but held against longitudinal movement on the rod. These tripping devices correspond in number with the registering-wheels 16.

The upper portions 19 of the tripping devices are arranged in a group, preferably near the center of the registering mechanism. 15 One of them, the central one in the construction shown, will be directly above the actuating mechanism controlled by it, so that its horizontal portion 21 extends backward in the plane of the upper portion 19 and vertical portion 20. The other tripping devices each have between the vertical portion 20 and the rearwardly-extending portion 21 a horizontal portion 24, extending in a direction parallel with the rod 17 to the right or 25 left, as the case may be, a distance sufficient to bring the rearwardly-extending portion 21 in the plane of the actuating mechanism controlled by it. The tripping devices at the right of the center will have their horizontal 30 portions 24 extend to the left, and those at the left of the center will have their horizontal portions 24 extend to the right. The upper portion 19 of the tripping device at the extreme right of the group, being the upper 35 portion 19 first struck by the device carried by the paper-carriage, will be arranged through the horizontal portion 24 and rearwardly-connected portion 21, connected with it, to bring into operative position the actuating devices for the registering-wheel at the 40 extreme left, which in the mechanism shown, which has nine registering-wheels, will be, if numbers are to be written without indications of denominations, the hundred-millions wheel. If numbers representing dollars and cents are to be written, this wheel 45 will be the millions-wheel. The tripping device at the extreme left, being the device last struck, will be arranged to bring into operative 50 position the actuating devices for the registering-wheel at the extreme right, which will be the units-wheel. The arrangement of these tripping devices is clearly shown in Figs. 3 and 5.

55 The downwardly-extending arm 23 has at its upper end a sleeve 25, surrounding the rod 17. These sleeves 25 are preferably of such length that they fill the length of the rod and are thus prevented from longitudinal movement. The sleeve 22 surrounds and rocks with the sleeve 25 and is provided with a longitudinal slot 23', which fits over the arm 23. The sleeve 22 is thus permitted movement longitudinally of the rod without 60 moving the arm 23, and at the same time any rocking of the sleeve 22 rocks the arm 23.

To the rear and above the plane of the rod

15, which carries the registering-wheels, is a stationary rod 27, supported by the end plates 5, on which are so carried as to freely rock 70 thereon the double-armed pawls 28 of the carrying mechanism, which will be more fully hereinafter described.

Above and in front of the main shaft 7 is a stationary rod 26, carrying detent-pawls 104. 75

Below the plane of the rod 15 and near the front of the device is a rocking plate 29, pivoted at its ends to the end plates 5, to which are secured a series of stop-arms 30, each of which is arranged in the path of one of the 80 segmental racks by which the registering-wheels 16 are operated, and are adapted through arms 31, also secured to the rocking plate 29, (see Figs. 12 and 13,) to be moved into position to stop the movement of the racks to 85 prevent overthrow, as more fully described hereinafter.

Below the main shaft 7 and preferably toward the front of the device is a stationary guide-rod 32, carried by the end plates 5. 90

Journalled on a split bushing 11', secured to the sleeve 11, which serves also as end bearings, so as to rock freely thereon, are a number of levers 33. (Shown in detail in Figs. 9 and 20.) These levers are nine in number to 95 correspond with the nine numeral-keys of the type-writing machine. In order to prevent lateral movement of these levers, they each have a double bearing on the split bushing by means of an arm 34, secured to the lever 100 33. These levers are each arranged in proximity to one of the radial arms 9 and are each provided with a projection 35, preferably on the arm 34, bent at a right angle and adapted to engage the rear of one of the arms 9, so 105 as to carry the arm forward with it, rocking the shaft 7. The projection 35 will be positioned on the several levers at different points corresponding with the unit values of the different numerals. The lever or the arm 34, as 110 the case may be, carries, in addition to the projection 35, a rearwardly-extending arm 36, adapted to engage the under side of a locking-bail 89, hereinafter described, and carries also a downwardly-extending arm 37, adapted to 115 contact with the guide-rod 32 to stop further upward movement of the lever. The arms 36 and 37 are in the same plane as the part on which they are carried. The lever carries also a projection 38 bent at right angles and 120 perforated for the attachment of a spring 39, by which the lever is returned to place after being depressed.

Pivotedly connected to each of the levers 33 at 40 is a link 41, connecting the lever with 125 the key-lever of one of the numeral-keys of the type-writing machine, so that as the numeral-key is depressed to print the lever 33 connected with it will also be depressed, causing, as the projection 35 comes in contact 130 with the radial arm 9, the main shaft 7 to be rocked through a greater or less arc.

The link 41 is preferably made in two parts 42 and 43, as shown, the two parts having a

screw connection 44 for the purposes of adjustment. The lower part 43 is provided at its lower end with an open slot 45, adapted to fit a pin 46, carried in any convenient manner by the key-lever of the machine. The part 43 is preferably also provided with a slot 47, with which a rod 48, carried by levers 49, engages for the purpose of locking the link out of connection with the type-lever when desired.

In the ordinary use of the type-writing machine, even when the levers 33 are connected to the numeral-keys, these keys may be operated without effecting any movement of any part of the registering mechanism except the depression of the levers 33 and the rocking of the main shaft.

The levers 33 are extended forward to form operating-handles 33', by which they may be operated independently of the type-writing keys.

The devices by which the rocking of the main shaft is caused to actuate the registering mechanism are arranged in groups corresponding in number with the registering-wheels 16. Each of these groups comprises a bearing-piece 50, supported by and turning freely on the sleeve 11, a pawl-carrier 51, arranged to rock on the sleeve 11, a pawl-carrier 52, arranged on the bearing-piece, the pawl-carriers 51 and 52, carrying, respectively, pawls 53 and 54, a cam-plate 55 between the pawl-carriers in proximity to the pawl-carrier 51, arranged to have vertical movement, but not to have rocking movement and a segmental rack 56 in proximity to the pawl-carrier 52 and arranged to have both vertical and rocking movement. In its rocking movement this rack moves with the pawl-carrier 52 in both forward and return movement, and in its vertical movement it moves independently of this pawl-carrier. In both its movements it is independent of the pawl-carrier 51.

The bearing-piece 50 has formed thereon a central disk or shoulder 57 and on one side thereof a bearing 58 for the cam-plate adapted to turn freely within an opening in the cam-plate and to permit and guide its vertical movement. It also has on the opposite side a non-circular portion 59, adapted to fit within an opening in the segmental rack 56 and to permit its vertical movement without rocking movement relative to the bearing-piece. The pawl-carrier 52 is supported on a portion 60 of the bearing-piece and is secured to the bearing-piece by riveting or otherwise. The several elements carried by the bearing-piece are held together between the pawl-carrier 52 on one side of the group of elements and by a washer 61, riveted or otherwise secured to the bearing-piece, on the other side.

The pawl 53 is pivoted to a rearward extension 62 of the pawl-carrier 51 and is so arranged that its forward hooked end 63 is in the plane of one of the arms 9, so that when depressed it will be engaged by the end of

this arm. A spring 64, secured at one end to a projection 65 on the pawl-carrier, presses by its free end against the rear end of the pawl below its pivot-point, so that the forward end of the pawl is normally raised out of engagement with the arm 9.

The pawl 53 has at a point forward of its pivot a rearwardly and upwardly extending finger 66. When the registering devices are in the position of rest, this finger 66 lies directly in the path of and preferably in contact with the depending arm 23, so that the forward rocking movement of this arm will cause the pawl to rock on its pivot, depressing its forward hooked end 63 into position to be engaged by the arm 9, so that as the arm is rocked forward it will carry the pawl and its pawl-carrier forward with it.

The pawl-carrier 51 carries on the side next the cam-plate 55 a roller 67 and has on its front edge a projection so positioned as to be immediately behind the end of the arm 9 when it is engaged by the hooked end 63 of the pawl and has also a rearwardly-extending finger 79, adapted to strike the finger 73 of the cam-plate 55 on the return movement of the pawl-carrier, and thus to stop it in proper position.

The cam-plate 55 has its upper edge curved, as shown in detail in Fig. 18, this edge being bent over toward the pawl-carrier 51 to form a flange 68. The rear end of this flange is bent upward, as shown at 69. The cam-plate 100 is provided with an opening 70 to fit over the bearing-piece and in an extension has an opening 71 to fit over the guide-rod 32. The openings 70 and 71 are of such form as to permit the cam-plate to move freely in a vertical direction.

When the registering devices are in a position of rest, the roller 67 of the pawl-carrier 51 lies immediately in rear of the upwardly-bent end 69 of the flange of the cam-plate. As the pawl-carrier is moved forward by the action of the arm 9 after the pawl 53 has been caused to engage it by depending arm 23 this roller 67 will as it comes in contact with the end 69 cause the cam-plate to 115 be lifted until the roller can pass beneath the main portion of the flange 68. As the pawl-carrier continues its forward movement the roller 67 will sustain the cam-plate in its raised position. The cam-plate is also provided with 120 a rearward extension which carries two fingers 72 and 73, bent at right angles to the main portion of the cam-plate and extending in opposite directions, the finger 72 being above and to the rear of the finger 73. The 125 finger 72 is of sufficient length to extend past the segmental rack 55 into the plane of the pawl 54 of the pawl-carrier 52, and when the devices are in position of rest the end of this finger is immediately below the tailpiece 82 of the pawl 54, so that as the cam-plate is lifted it will cause this pawl to turn on its pivot to depress its forward end. The finger 73 lies in the plane of movement of the pawl-

carrier 51 and forms a stop against which the projection 79 on the pawl-carrier strikes to prevent its further rearward movement after it has returned to position. The segmental rack 56 carries on the side next the cam-plate a roller 74, so placed as to ride upon the flange 68. The rack has an opening 75 formed therein adapted to fit over and to slide on the non-circular portion 59 of the bearing-piece and has at its lower end means for attachment of a spring 76, by which the rack is drawn downwardly and turned to its rearmost position, the lower end of the spring 76 being secured to a stationary rod 77. The rack has on its upper edge ten teeth adapted when raised into operative position to mesh with the teeth of the pinion 16' of the registering-wheel 16. The pawl-carrier 52 is secured by a rivet 80 or otherwise to the non-circular portion 59 of the bearing-piece. To its upper portion is pivoted the pawl 54. The forward portion of this pawl is of substantially the same shape as but slightly longer than the corresponding portion of the pawl 54 and has the hooked end 81, adapted to be engaged by the upper end of an arm 9. The pawl has a tailpiece 82, which normally rests directly above the finger 72 of the cam-plate, as above stated. A spring 83, secured at its lower end to the pawl-carrier, bears at its free end against the rear end of the pawl, holding the forward end of the pawl normally raised.

The pawls 53 and 54 are each provided forward of their pivots with an upwardly-extending arm 84, adapted to bear against the under side of a curved guide-plate 85, which is secured at its ends to the end plates 5, so that as the pawls move forward their forward ends are prevented from being raised out of engagement with the arms 9. From this description it will be seen that by pressing rearward the upper end of one of the tripping devices the depending arm 23 will be swung forward against the projection 66 of the pawl 53, depressing the forward end of the pawl into position to engage one of the arms 9. As one of the numeral-keys is depressed, drawing down the lever 33, the main shaft, with its arms 9, will be rocked by the action of the projection 35 of the arm 34 against the arm 9, with which it is adapted to contact, and the arm 9, lying in the plane of the pawl 53, will engage the hooked end 63 and draw the pawl and with it the pawl-carrier 51 forward. As the pawl-carrier 51 moves forward the roller 67, coming in contact with the under side of the inclined end 69 of the flange 68, will cause the cam-plate to move vertically upward, lifting with it, through the roller 74, the segmental rack 56. At the same time the finger 72 of the cam-plate lifts the tailpiece of the pawl 54, depressing its hooked end 81 into the path of the arm 9, which lies in the plane of this pawl. The further forward movement of this arm 9 carries the pawl 54, its carrier 52, and the segmental rack 56 forward to effect the rotation of the

registering-wheel 16. As the lever 33 is depressed by the depression of the numeral-key a pin or screw 86, carried by it, enters the open slot 87 in the arm 31 and continues until it is stopped in the operation of the type-writing machine by the striking of the type-bar against the platen or in the operation of the calculating-machine as a separate device against the end of the slot. The slot 87 being cam-shaped, the pin or screw causes the arm 31, and with it the rocking plate 29, to which the arm is attached, to rock on its pivots to carry the stop-arm 30 into the position to strike the forward edge of the segmental rack 56 to stop it at the completion of its movement. The shape of the cam-slot 87 in the arm 31 will differ for the several arms corresponding to the different numeral-keys, so as to move the stop-arm the distance necessary in each case. For instance, the slot in the arm 31 corresponding to the "9" key will be of such shape that the stop-arm 30 will meet and stop the segmental rack only when nine of the teeth have successively acted upon the teeth of the pinion 16' to turn the registering-wheel nine spaces. The slot in the arm 31 corresponding to the "1" key will be of such shape as to quickly rock the plate 29, so that the stop-arm 30 will meet and stop the segmental rack when it has caused the registering-wheel to turn through one space. As the full stroke of the lever 33 is completed it acts, through a finger 36, to release the locking-dog of a full-stroke device, so that on the release of the numeral-key the several elements are free to resume their normal position. This return to normal position takes place as follows: The main shaft 7, with the arms 9, is returned to normal position by the spring 8. As the arm 9, which was engaged by the hooked end 63 of the pawl 53, returns under the force of the spring 8 it strikes the projection 78 of the pawl-carrier 51, and thus causes the pawl-carrier 51, with its pawl 53 and its roller 67, to return with it, the roller 67 being thus carried backward away from beneath the flange 68 of the cam-plate. The segmental rack is momentarily held in its advance position, as its teeth are still in engagement with the teeth of the pinion 16' of the registering-wheel 16, which is held against backward movement by the detent-pawl 104. As soon, however, as the roller 67 is carried back from beneath the flange 68 of the cam-plate the cam-plate, being no longer supported against the force of the spring 76, drops, and with it the segmental rack drops, and as its teeth are then out of mesh with the teeth of the pinion 16' it is instantly returned to normal position by the force of the spring 76.

Extending from one end plate 5 to the other is a locking-bail 89, which forms part of the device by which a full stroke of the lever 33 is insured. This bail is supported at its ends by rearward extensions 92 of bail-supporting levers 90 and 91, which are carried by and rock freely on the sleeve 11. One of these

bail-supporting levers, preferably that at the left of the mechanism indicated by reference-numeral 90, is provided with a downwardly-extending finger 93, adapted to strike against 5 the rear of the rod 32 to prevent the bail from dropping below its normal position. The bail-supporting-lever 91, preferably arranged at the right of the mechanism, is provided with a forwardly-extending finger 94 and with a 10 projection 95 in rear of its bearing on the sleeve 11. Pivoted to the end plate 5 above and forward of the main shaft 7 and preferably directly above the rocking plate 29 is swinging deterrent-lever 96. Also pivoted to the 15 end plate 5, but at a point above and to the rear of the main shaft 7, is a toothed dog 97. A spring 98, connected at one end to this toothed deterrent above its center and at the other end to the swinging deterrent-lever 96, 20 tends to press the forward end of the dog 97 downward and to draw the lower end of the deterrent-lever 96 rearward against the end of the finger 94.

The rocking plate 29 is provided with an 25 upwardly-extending arm 99, having its upper end toothed to engage the teeth of the toothed dog. As the rocking plate 29 is rocked by the action of the pin or screw 86 of the lever 33 on the cam-slot 87 the teeth of the arm 99 30 will move along the under surface of the dog 97 and by engaging the teeth of this dog will be prevented from moving backward until the dog is raised. The rocking plate 29 and the arms 30 and 31 carried by it will consequently be prevented from resuming normal 35 position until the dog 97 is raised to release the arm 99. As the lever 33 completes its stroke its rearward projection 36 will strike the under side of the bail 89, lifting it and 40 through the extension 92 of the bail-supporting levers 90 and 91 causing these levers to rock on the sleeve 11. As the bail-supporting lever 91 is thus rocked its projection 95 strikes a shoulder 100 on the toothed dog 97 45 below and forward of its pivot. This raises the forward end of the dog against the force of the spring 98 and releases the lever 99, permitting the rock-shaft to resume its normal position. At the same instant that the projection 95 on the bail-supporting lever strikes the shoulder 100 on the dog 97 its finger 94 50 passes below a shoulder 101 on the deterrent-lever 96, by which it is engaged, thus holding the bail-carrying lever in such position that it in turn holds the dog 97 in its raised 55 position out of engagement with the teeth of the arm 98. The parts are held in this position until the rocking plate, with its arms 30 and 31, resumes its normal position. As it resumes 60 its normal position a stop 102, carried by the arm 99, preferably made adjustable, as shown, strikes the lower end of the deterrent 96, throwing it forward, releasing the finger 94 and permitting the bail-carrying levers and the dog 97 to resume their normal positions.

By the above construction it will be seen that after the lever 33 has begun its move-

ment it cannot be brought back to its normal position except by continuing its movement to completion of its full stroke.

70

The registering-wheel 16 carries on the side opposite to the pinion 16' a ratchet-wheel 103, with which a detent-pawl 104 engages to prevent backward movement of the registering-wheel after it has once been rotated. For the 75 purpose of carrying from the units-wheel to the tens-wheel, from the tens-wheel to the hundreds-wheel, and so on, I provide the carrying mechanism, which I will now describe.

Each of the registering-wheels except the 80 highest is provided on the side toward the next higher wheel with a radial pin 105, preferably bent to the form shown in Fig. 31, and the periphery of the wheel is cut away, as shown in Figs. 30 and 31, to form a cam-surface, as shown. Each of the registering-wheels except the units-wheel is provided on the same side as the pinion 16' with a ratchet-wheel 106, secured to the pinion.

85

Carried by the stationary rod 27, so as to 90 rock freely thereon, is a double-armed carrying-pawl 28, the two arms 107 and 108 of which are arranged, respectively, in the planes of the radial pin 105 of a lower registering-wheel and in the plane of the ratchet-wheel 95 106 of the next higher registering-wheel. The arm 107 is forked, as shown in Fig. 30, the end of its lower finger 109 lying in the path of the pin 105 and its upper finger 110 being in position when the finger 109 is depressed by the pin 105 to ride upon the cut-away portion of the registering-wheel, and as the registering-wheel continues its rotation the finger 110, riding up upon the main portion of the wheel, will raise the lower finger 109 105 to normal position. The arm 108 of the carrying-pawl has pivoted to it at its forward end the forward end of a pawl 111, the rear end 112 of which is of sufficient weight to insure the pawl swinging forward, as shown in Figs. 110 26 and 27, to engage the ratchet-wheel 106 of the higher registering-wheel. The tooth 113 of the pawl 111 is made with parallel front and rear edges, as shown in Figs. 26 and 27. Secured to the guide-plate 85 is an upright 115 arm 114, having at its upper end a projection 115, so shaped that it forms a guide for the tooth 113 of the pawl 111, the tooth 113 when brought down to advance the higher 120 registering-wheel one space fits snugly between the ratchet-wheel 106 and this projection and is thus prevented from moving the higher wheel more than the one space necessary for carrying. If the lower registering-wheel is further rotated, the finger 110 will 125 be raised as it passes off the cut-away portion of the wheel, and the arm 108 and its pawl 111 will be raised, leaving the higher registering-wheel free to be again rotated. If, however, as will ordinarily be the case, it is 130 necessary to rotate the higher registering-wheel before the lower wheel has been rotated sufficiently to lift the pawl 111, it will be necessary to provide other means for lift-

ing the pawl 111 to free the registering-wheel. The means which I provide for this purpose consists of an upwardly-extending arm 115, secured to the cam-plate 55 of the higher wheel and having its upper end arranged to come in contact when lifted by the cam-plate with a projection 116, carried by the arm 108, to raise the arm and with it the pawl 111.

In order to prevent the lateral movement 10 of the double-armed pawls 28 on the rod 27, I secure to the rod between the arms 107 and 108 a collar 117. (Shown in detail in Fig. 29.) This collar is firmly clamped on the rod, as shown, and is provided with an extension 15 118, bent at right angles and fitting over the collar 119 of the rod on which the registering-wheels 16 are carried.

It will be understood that the cam-plate 55 of the units-registering mechanism will not 20 need to be provided with the upright arm 115.

For the purpose of disconnecting the registering mechanism as a whole from the typewriter keys the levers 49, which, as above described, carry at their lower ends a rod 48, 25 which rests in the slots 47 of the links which connect the levers 33 with the respective numeral-keys, are provided with a rearward-extending arm 118, which is arranged to be engaged by a ratchet in the latch 119 when 30 the links are pushed backward to disconnect them from the numeral-keys. This latch is drawn forward by a spring 120, which also serves to draw the lever 49 forward. An arm 121 on the lever 49 by contacting with the rod 32 prevents forward movement of the 35 lower end of the lever beyond the point at which the lower ends of the links are in operative engagement with the numeral-keys.

In writing numbers to be added it is usually 40 found desirable to insert commas to point off into periods of three figures each, and in writing numbers representing dollars and cents it is desirable to insert a period between the dollars and the cents. For the 45 purpose of adapting my device for this purpose I provide means by which the tripping devices 18 may be shifted longitudinally of the calculating mechanism. The sleeves 22, as before described, are each provided with a 50 rearwardly-extending pin 22', and these pins are arranged to be engaged by open-ended slots 122 in plates 123 124 125, which are carried by levers 126, one or both of which may be forwardly extended to enable the plates to 55 be readily moved vertically. One of these levers 126 is arranged at each end of the calculating device and is pivotally mounted on the shaft 27. One of these plates—as, for instance, plate 123—has its slots 122, arranged 60 as shown in Fig. 4—that is, with the two slots at the right of Fig. 4, (the left of the calculating mechanism, since Fig. 4 is a rear view) being inclined away from the center, both at the same angle, with the next 65 three slots vertical, with the next three slots inclined in the opposite direction to that of the first two slots and all inclined at the same

angle, and with the last slot inclined in the same direction, but at a greater angle. When this plate is pressed downward by raising the 70 forward end of the levers 126, its slots, engaging the pins 22', will shift the sleeves 22 of the tripping devices which control the lowest two registering devices away from the others, so as to open a space between them and the 75 others, in which space should be printed the period separating the two cents-columns from the dollars. The next three sleeves will not be shifted, the slots being vertical. The following three sleeves will be shifted to open a 80 space for the insertion of a comma between the hundreds-figure and the thousands, and the last sleeve will be shifted sufficiently to permit of the insertion of a comma between the hundred thousands and the millions. The 85 plate 124 has the first three of its slots 122 parallel and inclined away from the center, so as to simultaneously shift the tripping devices of the lowest three registering devices a sufficient distance to permit a comma to 90 be inserted between the hundreds and thousands, has its next three slots vertical to retain the tripping devices of the thousands, ten thousands, and hundred thousands registering devices in normal position, and has the 95 last three slots all inclined at the same angle in a direction opposite to the direction of the first three slots in order to shift the tripping devices of the millions, ten millions, and hundred millions registering devices a sufficient 100 distance to permit a comma to be inserted between the hundred thousands and the millions. The third plate 125 has its slots 122 equal distances apart at their upper ends, but having their open ends sufficiently wide to 105 engage the pins 22' of the sleeves 22 in any position to which they may have been shifted, so that when this plate is depressed it will return the sleeves and the tripping devices to normal position. In the use of these shifting 110 devices after the plate 123 or the plate 124 has been depressed to arrange the tripping devices for dollars and cents or for pointing off the plate 125 should be depressed to return them to normal position before the other 115 plate is depressed.

On the front plate of the calculating mechanism is preferably arranged a series of guide-plates 127, 128, and 129 for holding the front 120 ends of the tripping devices in position and preventing them from being moved sidewise by the tripping-cam carried by the carriage. These plates are slotted, as shown, the slots being arranged to correspond with the slots of the plates 123, 124, and 125. These guide- 125 plates are placed one in front of the other and have end slots 130, through which hand-screws 131 extend and by which they may be clamped in position. They are each preferably provided with downwardly-extending 130 projections 132, by which they may be readily raised or pulled down.

Carried by the paper-carriage is a cam 133, arranged when in operative position to strike

as the carriage travels the end 19 of the several tripping devices 18 in succession. This cam is preferably formed on the end of arm 134, hinged to a plate 135, which is supported 5 on a carrier-bar 136, secured by the bent arms 137 to the paper-carriage. A screw 138, carried on the plate 135 and bearing against the carrier-bar 136, forms a convenient means for adjusting the position of the plate and the 10 cam 133. The plate 135 is preferably provided with a pointer 139, so arranged as to slide upon the indicator-scale of the machine to enable the cam 133 to be readily set at the proper point. A spring 140, secured at its 15 upper end to the plate 135 and pressing outward at its lower end against a portion 141 of the hinged arm 134 above its pivot, tends to press the cam 133 inward, so that it will be in position to strike the ends 19 of the tripping devices. A screw 142, extending through the arm 134 below the pivot and bearing against the plate 135, serves when screwed inward to force the cam 133 away from its operative position against the force of the 20 spring 140.

The carrier-bar 136 may be of any length desired and may be supported from the paper-carriage in any convenient way, it being essential only that it so support the cam 133 30 that this cam in the operation of the machine will be in position to strike the ends of the tripping device and cause them to throw the registering devices into position to be operated when one of the numeral-keys is operated 35 at.

In the use of the machine the cam 133 will be so set on the carrier-bar that it will come in contact with and press back the first of the tripping devices—that is, the tripping device 40 farthest to the right—as the point on the paper carried by the paper-carriage comes in position to have printed thereon the first figure of the number to be written, and the successive numbers will be written in column 45 beneath the first, units coming under units, tens under tens, &c. As the successive numbers are written the total will appear on the registering-wheels. When it is desired to write the total, by turning the screw 142 the cam 50 133 will be forced out of operative position and the total may be written without effecting any further operation of the registering devices. The registering-wheels may then be reset to zero, or, if desired, the total may 55 be carried over to the top of the next sheet and the adding operation continued.

The resetting of the registering-wheels to zero may be effected by any well-known device. In the preferred form of device for 60 this purpose I provide the rod 15 with a series of pins 143, one for each of the registering-wheels, normally out of contact with the radial pins 105, but capable of being brought into contact with these radial pins when the 65 rod 15 is moved longitudinally. For moving the rod 15 longitudinally and for rotating it I provide it with a milled head 144. The rod

is also provided with a pin 145, adapted to enter a notch 146 in the end plate 5, and the rod is also provided with a spring 147, bearing at one end against the inner side of the end plate and at the other end bearing against a pin 148, carried by the rod. In order to prevent longitudinal movement of the registering-wheels, sleeves 149 are interposed between them and between the first and last of the series and the end plates. The front plate 6 is 70 preferably made in two parts 6' and 6'', and these parts are secured in any convenient manner to the end plates 5. The lower part 80 6' of the front plate is provided with slots for the levers 33 and also has a slot 153, through which extends the end of the toothed dog 97 of the full-stroke device. The upper part 6'' of the front plate is provided with a series of 85 openings 154, at which the numbers on the registering-wheels appear, and is also provided with slots 155, 156, and 157, through which extend the forward ends of the levers 126, by which the shifting of the tripping devices is effected. At a convenient point, 90 preferably below the openings 154, a rotary indicator 158 is mounted, having at one end a milled head 159 for rotating it. This indicator carries on one face at points between 95 the third and fourth and between the sixth and seventh registering-wheels commas and on another face carries between the second and third registering-wheels a period and between the fifth and sixth registering-wheels a 100 comma.

The cam 133 may be carried by any moving part of the machine other than the carriage, if preferred. In using the device as a calculating-machine separate from the type-writing machine the tripping devices may be operated in succession by any convenient device and, if desired, may be operated in the opposite order from that in which they are operated by the carriage of the type-writing machine.

I have shown the calculating-machine arranged on the front of the type-writing machine and immediately above and in rear of the keyboard, and while I regard this as the 115 most desirable position, as the registering-wheels are thus in convenient position to be seen by the operator, I do not desire to be understood as limiting my invention to this particular arrangement, as the machine may be 120 placed in any relation to the operating parts of the type-writing machine so long as it is so placed that it may be operated by the type-levers, and while my invention is shown in connection with a particular type of type-writing machine it may evidently without material change be adapted for use with type-writing machines of other types. So, also, while I have indicated the preferred arrangement of the tripping devices it will be 125 understood that these devices may be arranged to be operated by a device carried on any moving part of the type-writing machine and may extend into the path of such device,

whether such device be carried above or below the top plate of the machine or in the front or rear of the carriage.

It will be obvious that many changes may be made in the form and arrangement of the several elements of the machine without departing from the spirit of the invention.

Having thus described my invention, what I claim as new, and desire to secure by Letters Patent, is—

1. In a calculating-machine the combination of a registering-wheel and mechanism for actuating it, normally disconnected means for operating the mechanism for actuating the registering-wheel, a tripping device arranged, when operated, to throw the mechanism for actuating the registering-wheel into position to be operated by its operating means for shifting the position of the tripping device, and means for actuating the tripping device; substantially as described.

2. In a calculating-machine the combination of a registering-wheel and mechanism for actuating it, normally disconnected means for operating the mechanism for actuating the registering-wheel, a tripping device arranged, when operated, to throw the mechanism for actuating the registering-wheel into position to be operated by its operating means, and adjustable means for automatically actuating the tripping device; substantially as described.

3. In a calculating-machine, the combination of a series of registering-wheels and mechanisms for actuating them, means for separately operating the mechanisms for actuating the registering-wheel normally disconnected therewith, a series of tripping devices, each arranged, when operated, to throw one of the mechanisms for actuating the registering-wheel into position to be operated by its operating means and a common means for actuating the several tripping devices; substantially as described.

4. In a calculating-machine, the combination of a series of registering-wheels and mechanisms for actuating them, means for separately operating the mechanisms for actuating the registering-wheel, normally disconnected therewith, a series of tripping devices, each arranged, when operated, to throw one of the mechanisms for actuating the registering-wheel into position to be operated by its operating means, and a common means for automatically actuating the tripping devices in succession; substantially as described.

5. In a calculating-machine, the combination of a series of registering-wheels and mechanisms for actuating them, means for separately operating the mechanisms for actuating the registering-wheels normally disconnected therewith, a series of tripping devices, each arranged, when operated, to throw one of the mechanisms for actuating the registering-wheels into position to be operated by its operating means, means for automatically actuating the tripping devices in succession and

means for shifting the position of one or more of the tripping devices relative to the others; substantially as described.

6. In a calculating-machine, the combination of a main shaft, a key-lever operating to rock the main shaft, a registering-wheel and mechanism for actuating it and a tripping device arranged, when operated, to throw the mechanism for actuating the registering-wheel into position to be operated by the rocking of the main shaft; substantially as described.

7. In a calculating-machine, the combination of a main shaft, a series of key-levers each operating to rock the main shaft, a registering-wheel and mechanism for actuating it and a tripping device arranged, when operated, to throw the mechanism for actuating the registering-wheel into position to be operated by the rocking of the main shaft; substantially as described.

8. In a calculating-machine, the combination of a main shaft, a key-lever operating to rock the main shaft, a series of registering-wheels and mechanism for actuating them and a series of tripping devices, each arranged, when operated, to throw one of the mechanisms for actuating the registering-wheels into position to be operated by the rocking of the main shaft; substantially as described.

9. In a calculating-machine, the combination of a main shaft, a series of key-levers each operating to rock the main shaft, a series of registering-wheels and mechanism for actuating them and a series of tripping devices, each arranged, when operated, to throw one of the mechanisms for actuating the registering-wheels into position to be operated by the rocking of the main shaft; substantially as described.

10. In a calculating-machine for use in connection with a type-writing machine, the combination of a main shaft, means connected to a numeral-key of the type-writing machine for rocking the main shaft, a registering-wheel and mechanism for operating it, a tripping device arranged, when operated, to throw the mechanism for actuating the registering-wheel in position to be operated by the rocking of the main shaft, and means carried by a moving part of the type-writing machine to operate the tripping device; substantially as described.

11. In a calculating-machine for use in connection with a type-writing machine, the combination of a main shaft, means connected to each of the numeral-keys of the type-writing machine for rocking the main shaft, a registering-wheel and mechanism for operating it, a tripping device arranged, when operated, to throw the mechanism for actuating the registering-wheels in position to be operated by the rocking of the main shaft, and means carried by a moving part of the type-writing machine to operate the tripping device; substantially as described.

12. In a calculating-machine for use in connection with a type-writing machine, the combination of a main shaft, means connected to a key of the type-writing machine for rocking the main shaft, a series of registering-wheels and mechanisms for operating them, tripping devices, each arranged, when operated, to throw one of the mechanisms for operating the registering-wheels in position to be operated by the rocking of the main shaft and means carried by a moving part of the type-writing machine to operate the tripping devices in succession; substantially as described.
13. In a calculating-machine for use in connection with a type-writing machine, the combination of a main shaft, means connected to each of the numeral-keys of the type-writing machine for rocking the main shaft, a series of registering-wheels and mechanisms for operating them, tripping devices, each arranged, when operated, to throw one of the mechanisms for actuating the registering-wheels in position to be operated by the rocking of the main shaft and means carried by a moving part of the type-writing machine to operate the tripping devices in succession; substantially as described.
14. In a calculating-machine for use in connection with a type-writing machine, the combination of a registering-wheel, mechanisms for actuating the registering-wheel, means connected with a key of the type-writing machine for operating the mechanism for actuating the registering-wheel, normally disconnected therewith, a tripping device arranged, when operated, to throw the mechanism for actuating the registering-wheel into position to be operated by its operating means, and means operated by the carriage of the type-writing machine for automatically actuating the tripping devices; substantially as described.
15. In a calculating-machine for use in connection with a type-writing machine, the combination of a series of registering-wheels, mechanisms for actuating the registering-wheels, means connected with a key of the type-writing machine for operating the mechanisms for actuating the registering-wheels normally disconnected therewith, a series of tripping devices arranged, when operated, to throw one of the registering mechanisms into position to be operated by the operating means, and means operated by the carriage of the type-writing machine for automatically actuating the tripping devices; substantially as described.
16. In a calculating-machine for use in connection with a type-writing machine, the combination of a registering-wheel, mechanism for actuating the registering-wheel, means connected with each of the numeral-keys of the type-writing machine for operating the mechanism for actuating the registering-wheels, normally disconnected therewith, a tripping device arranged, when operated, to

throw the registering mechanisms into position to be operated by the operating means, and means operated by the carriage of the type-writing machine for automatically actuating the tripping device; substantially as described.

17. In a calculating-machine for use in connection with a type-writing machine, the combination of a series of registering-wheels, mechanisms for actuating the registering-wheels, means connected with a key of the type-writing machine for operating the mechanisms for actuating the registering-wheels, normally disconnected therewith, a series of tripping devices arranged, when operated, to throw one of the mechanisms for actuating the registering-wheels into position to be operated by its operating means, means operated by the carriage of the type-writing machine for automatically actuating the tripping devices, and means for shifting the position of one or more of the tripping devices relative to the others; substantially as described.

18. In a calculating-machine for use in connection with a type-writing machine, the combination of a series of registering-wheels, mechanisms for actuating the registering-wheels, means connected with each of the numeral-keys of the type-writing machine for separately operating the mechanisms for actuating the registering-wheels, normally disconnected therewith, a series of tripping devices arranged, when operated, to throw one of the mechanisms for actuating the registering-wheels into position to be operated by its operating means, means operated by the carriage of the type-writing machine for automatically actuating the tripping devices, and means for shifting the position of one or more of the tripping devices relative to the others; substantially as described.

19. In a calculating-machine for use in connection with a type-writing machine, the combination of a registering-wheel, mechanism for actuating the registering-wheel, means connected with a key of the type-writing machine for operating the mechanism for actuating the registering-wheel, normally disconnected therewith, a tripping device arranged, when operated, to throw the mechanism for actuating the registering-wheel into position to be operated by the operating means, and a device carried by the carriage of the type-writing machine arranged to actuate the tripping device; substantially as described.

20. In a calculating-machine for use in connection with a type-writing machine, the combination of a registering-wheel, mechanism for actuating the registering-wheel, means connected with each of the numeral-keys of the type-writing machine for operating the mechanism for actuating the registering-wheels, normally disconnected therewith, a tripping device arranged, when operated, to throw the mechanism for actuating the registering-wheel into position to be operated by

the operating means, and a device carried by the carriage of the type-writing machine arranged to actuate the tripping device; substantially as described.

5 21. In a calculating-machine for use in connection with a type-writing machine, the combination of a registering-wheel, mechanism for actuating the registering-wheel, means connected with a key of the type-writing machine for operating the mechanism for actuating the registering-wheel, normally disconnected therewith, a tripping device arranged, when operated, to throw the mechanism for actuating the registering-wheel into position 10 to be operated by the operating means, a device carried by the carriage of the type-writing machine arranged to actuate the tripping device, and means for moving the device carried by the carriage out of position to actuate 15 the tripping devices; substantially as described.

22. In a calculating-machine for use in connection with a type-writing machine, the combination of a registering-wheel, mechanism 25 for actuating the registering-wheel, means connected with each of the numeral-keys of the type-writing machine for operating the mechanism for actuating the registering-wheel, normally disconnected therewith, a 30 tripping device arranged, when operated, to throw the mechanism for actuating the registering-wheel into position to be operated by the operating means, a device carried by the carriage of the type-writing machine arranged 35 to actuate the tripping device, and means for moving the device carried by the carriage out of position to actuate the tripping devices; substantially as described.

23. In a calculating-machine, the combination of a registering-wheel provided with a 40 pinion, mechanism for actuating the registering-wheel, comprising a main shaft arranged to rock on its axis, a segmental rack normally out of engagement with the pinion, so mounted as to be movable vertically relative to the shaft and to rotate on an axis concentric with the axis of the shaft, means actuated by the shaft for raising the rack into engagement with the pinion and for moving the rack 45 50 while in its raised position to rotate the registering-wheel, means for rocking the main shaft and means for lowering the rack out of engagement with the pinion and for returning it to normal position; substantially as described.

24. In a calculating-machine, the combination of a registering-wheel provided with a pinion, means for preventing backward movement of the registering-wheel, mechanism for 55 60 actuating the registering-wheel, comprising a main shaft arranged to rock on its axis, a segmental rack normally out of engagement with the pinion, so mounted as to be movable vertically relative to the shaft and to rotate on an axis concentric with the axis of the shaft, means actuated by the shaft for raising the 65 rack into engagement with the pinion and for

moving the rack while in its raised position to rotate the registering-wheel, means for rocking the main shaft and means for lowering the rack out of engagement with the pinion and for returning it to normal position; 70 substantially as described.

25. In a calculating-machine, the combination of a registering-wheel provided with a 75 pinion, mechanism for actuating the registering-wheel, comprising a rack normally out of engagement with the pinion, means for raising the rack into engagement with the pinion, means for moving the rack while in its raised 80 position to rotate the registering-wheel, means for lowering the rack out of engagement with the pinion and for returning the rack to normal position and a common means for actuating the means for raising and the means for 85 moving the rack; substantially as described.

26. In a calculating-machine, the combination of a registering-wheel provided with a pinion, means for preventing backward movement of the registering-wheel, mechanism for 90 actuating the registering-wheel, comprising a rack normally out of engagement with the pinion, means for raising the rack into engagement with the pinion, means for moving the rack while in its raised position to rotate 95 the registering-wheel, means for lowering the rack out of engagement with the pinion and for returning the rack to normal position and a common means for actuating the means for raising and the means for moving the rack; 100 substantially as described.

27. In a calculating-machine, the combination of a registering-wheel, provided with a pinion, means for preventing backward movement of the registering-wheel, mechanism for 105 actuating the registering-wheel comprising a rack normally out of engagement with the pinion, means for raising the rack into engagement with the pinion, means for moving the rack while in its raised position to rotate 110 the registering-wheel, means for positively stopping the movement of the rack at a pre-determined point, means for lowering the rack out of engagement with the pinion and for returning the rack to normal position, and 115 a common means for actuating the means for raising the rack, for moving the rack and for moving the stopping means into position to effect its function; substantially as described.

28. In a calculating-machine, the combination of a registering-wheel, provided with a pinion, means for preventing backward movement of the registering-wheel, mechanism for 120 actuating the registering-wheel comprising a rack normally out of engagement with the 125 pinion, means for raising the rack into engagement with the pinion, means for moving the rack while in its raised position to rotate the registering-wheel, means for positively stopping the movement of the rack at a pre-determined point, means for lowering the 130 rack out of engagement with the pinion and for returning the rack to normal position, means for locking the rack against rearward

movement until it has completed its movement, and a common means for actuating the means for raising the rack, for moving the rack and for moving the stopping means into 5 position to effect its function; substantially as described.

29. The combination of a shaft carrying a pinion, mechanism for actuating the pinion, comprising a main shaft arranged to rock on 10 its axis, a segmental rack normally out of engagement with the pinion, so mounted as to be movable vertically relative to the shaft and to rotate on an axis concentric with the axis of the shaft, means actuated by the shaft 15 for raising the rack into engagement with the pinion and for moving the rack while in its raised position to rotate the shaft carrying the pinion, means for rocking the main shaft and means for lowering the rack out of engagement with the pinion and for returning it to normal position; substantially as described.

30. The combination of a shaft carrying a pinion, means for preventing backward movement of the pinion, mechanism for actuating the pinion, comprising a main shaft arranged to rock on its axis, a segmental rack normally out of engagement with the pinion, so mounted as to be movable vertically relative to the 20 shaft and to rotate on an axis concentric with the axis of the shaft, means actuated by the shaft for raising the rack into engagement with the pinion and for moving the rack while in its raised position to rotate the shaft carrying the pinion, means for rocking the main shaft and means for lowering the rack out of engagement with the pinion and for returning it to normal position; substantially as described.

40 31. The combination of a shaft carrying a pinion, mechanism for actuating the pinion, comprising a rack normally out of engagement with the pinion, means for raising the rack into engagement with the pinion, means 45 for moving the rack while in its raised position to rotate the pinion, means for lowering the rack out of engagement with the pinion and for returning the rack to normal position and a common means for actuating the means 50 for raising and the means for moving the rack; substantially as described.

32. The combination of a shaft carrying a pinion, means for preventing backward movement of the pinion, mechanism for actuating the pinion, comprising a rack normally out of engagement with the pinion, means for raising the rack into engagement with the pinion, means for moving the rack while in its raised position to rotate the pinion, means for lowering the rack out of engagement with the pinion and for returning the rack to normal position and a common means for actuating the means for raising and the means for moving the rack; substantially as described.

65 33. In a calculating-machine, the combination of a main shaft, means for rocking the

main shaft, a stationary sleeve surrounding the main shaft, a registering-wheel, and mechanism carried by the sleeve and rotatable thereon, arranged to be operated by the main 70 shaft; substantially as described.

34. In a calculating-machine, the combination of a main shaft, means for rocking the main shaft, a stationary sleeve surrounding the main shaft and concentric therewith, a 75 registering-wheel, and mechanism carried by the sleeve and rotatable thereon, arranged to be operated by the main shaft; substantially as described.

35. In a calculating-machine, the combination of a main shaft, a stationary sleeve surrounding the main shaft, a registering-wheel and mechanism carried by the sleeve and rotatable thereon, arranged to be operated by the main shaft, and means for rocking the 80 main shaft also carried by the sleeve and rotatable thereon; substantially as described.

36. In a calculating-machine, the combination of a registering-wheel provided with a pinion and mechanism for actuating the registering-wheel comprising a segmental rack normally out of engagement with the pinion, provided with a roller, a cam-plate having a flange forming a track for said roller, means for raising the cam-plate to raise the segmental rack into engagement with the pinion of the registering-wheel and means for moving the rack to rotate the registering-wheel; substantially as described.

37. In a calculating-machine, the combination of a main shaft having radial arms, a registering-wheel provided with a pinion, mechanism for actuating the registering-wheel, comprising a segmental rack normally out of engagement with the pinion, provided with a roller, a cam-plate having a flange forming a track for said roller, means for raising the cam-plate to raise the segmental rack into engagement with the pinion of the registering-wheel, means for rocking the main shaft and means operated by the radial arms of the rock-shaft for raising the cam-plate to raise the segmental rack into engagement with the pinion of the registering-wheel and for moving the rack to rotate 110 the registering-wheel; substantially as described.

38. In a calculating-machine the combination of a main shaft having radial arms, a registering-wheel provided with a pinion, 120 mechanism for actuating the registering-wheel, comprising a segmental rack normally out of engagement with the pinion, provided with a roller, means for raising the rack into engagement with the pinion, comprising a cam-plate, having a flange forming a track for said roller, means for raising the cam-plate to raise the segmental rack into engagement with the roller comprising a pawl-carrier provided with a roller, arranged to engage the under side of the flange of the cam-plate, and a pawl adapted to engage one of

the radial arms of the main shaft, and means for rocking the main shaft; substantially as described.

39. In a calculating-machine the combination of a main shaft having radial arms, a registering-wheel provided with a pinion, mechanism for actuating the registering-wheel, comprising a cam-plate, a segmental rack normally out of engagement with the pinion provided with means for engaging the upper edge of the cam-plate, the cam-plate having a flanged upper edge, the flange being bent upward at its rear end, a pawl-carrier provided with means for engaging the under side of the flange of the cam-plate, normally arranged below the rear end of the flange of the cam-plate, a pawl pivotally mounted on the pawl-carrier having its forward end adapted to engage one of the radial arms of the main shaft, but normally out of engagement therewith, means for moving the pawl into position to engage the radial arm, and means for rocking the main shaft; substantially as described.

40. In a calculating-machine, the combination of a main shaft having radial arms, a registering-wheel provided with a pinion, mechanism for actuating the registering-wheel, comprising a segmental rack, adapted to engage the pinion, and means for moving the rack to rotate the registering-wheel comprising a pawl-carrier, a pawl pivotally mounted thereon, having its forward end adapted to engage one of the radial arms of the main shaft, means for moving the pawl to cause its engagement with the radial arm and means for rocking the main shaft; substantially as described.

41. In a calculating-machine, the combination of a main shaft having radial arms, a registering-wheel provided with a pinion, a segmental rack adapted to engage the pinion but normally out of engagement therewith, the segmental rack being provided with a roller, a cam-plate having a flanged upper edge adapted to form a way for the roller carried by the segmental rack, the rear end of the flange being bent upward, a pawl-carrier having a pawl adapted to engage one of the radial arms of the main shaft, but normally out of engagement therewith, the pawl-carrier being also provided with a roller normally arranged below the rear end of the flange of the cam-plate, means for causing the pawl to engage the radial arm, a second pawl-carrier having a pawl adapted to engage a second one of the radial arms of the main shaft, but normally out of engagement therewith, means carried by the cam-plate for causing the pawl of the second pawl-carrier to engage the radial arm, and means for rocking the main shaft; substantially as described.

42. The combination of a shaft carrying a pinion and mechanism for actuating the pinion, comprising a segmental rack normally out of engagement with the pinion, provided with a roller, a cam-plate having a flange

forming a track for said roller, means for raising the cam-plate to raise the segmental rack into engagement with the pinion and means for moving the rack to rotate the pinion; substantially as described.

43. The combination of a main shaft having radial arms, a shaft carrying a pinion, mechanism for actuating the pinion, comprising a segmental rack normally out of engagement with the pinion, provided with a roller, a cam-plate having a flange forming a track for said roller, means for raising the cam-plate to raise the segmental rack into engagement with the pinion, means for rocking the main shaft and means operated by the radial arms of the main shaft for raising the cam-plate to raise the segmental rack into engagement with the pinion and for moving the rack to rotate the pinion; substantially as described.

44. The combination of a main shaft having radial arms, a shaft carrying a pinion, mechanism for actuating the pinion, comprising a segmental rack normally out of engagement with the pinion, provided with a roller, means for raising the rack into engagement with the pinion, comprising a cam-plate, having a flange forming a track for said roller, means for raising the cam-plate to raise the segmental rack into engagement with the pinion, comprising a pawl-carrier provided with a roller, arranged to engage the under side of the flange of the cam-plate, and a pawl adapted to engage one of the radial arms of the main shaft, and means for rocking the main shaft; substantially as described.

45. The combination of a main shaft having radial arms, a shaft carrying a pinion, mechanism for actuating the pinion, comprising a segmental rack normally out of engagement with the pinion, provided with means for engaging the upper edge of a cam-plate, the cam-plate having a flanged upper edge, the flange being bent upward at its rear end, a pawl-carrier provided with means for engaging the under side of the flange of the cam-plate, normally arranged below the rear end of the flange of the cam-plate, a pawl pivotally mounted on the pawl-carrier having its forward end adapted to engage one of the radial arms of the main shaft but normally out of engagement therewith, means for moving the pawl into position to engage the radial arm, and means for rocking the main shaft; substantially as described.

46. The combination of a main shaft having radial arms, a shaft carrying a pinion, mechanism for actuating the pinion, comprising a segmental rack, adapted to engage the pinion, and means for moving the rack to rotate the pinion, comprising a pawl-carrier, a pawl pivotally mounted thereon, having its forward end adapted to engage one of the radial arms of the main shaft, means for moving the pawl to cause its engagement with the radial arm and means for rocking the main shaft; substantially as described.

47. In a calculating-machine, the combination of a registering-wheel, means for actuating the registering-wheel, comprising a segmental rack, and a lever for rocking the rack in one direction to rotate the registering-wheel, a stop arranged in the path of movement of the rack and means operated by the lever for moving the stop into position to prevent overthrow of the rack; substantially as described.

48. In a calculating-machine, the combination of a registering-wheel and means for actuating the registering-wheel, comprising a segmental rack and a series of levers each arranged, when operated, to rock the segmental rack in one direction to rotate the registering-wheel, a stop arranged in the path of movement of the rack and means operated by each of the levers for moving the stop into position to prevent overthrow of the rack; substantially as described.

49. In a calculating-machine, the combination of a series of registering-wheels, separate means for actuating the several registering-wheels, each comprising a segmental rack, a lever and means whereby the lever may rock any one of the racks in one direction to rotate its registering-wheel, means for returning the rack to normal position, a stop arranged in the path of movement of each of the several racks and means operated by the lever for moving one of the stops into position to prevent overthrow of the rack operated by the lever; substantially as described.

50. In a calculating-machine, the combination of a series of registering-wheels and separate means for actuating the several registering-wheels, each comprising a segmental rack, and a series of levers each arranged, when operated, to rock any one of the segmental racks in one direction to rotate one of the registering-wheels, a stop arranged in the path of each of the racks and means operated by each of the levers for moving the stop into position to prevent overthrow of the rack operated; substantially as described.

51. In a calculating-machine, the combination of a registering-wheel, means for actuating the registering-wheel, comprising a segmental rack, and a lever for rocking the rack in a forward direction to rotate the registering-wheel, means for returning the rack to normal position, a stop arranged in the path of movement of the rack, and means operated by the lever for moving the stop into position to prevent overthrow of the rack and means for locking the rack against return until it has completed its forward movement; substantially as described.

52. In a calculating-machine, the combination of a registering-wheel and means for actuating the registering-wheel, comprising a segmental rack and a series of levers each arranged, when operated, to rock the segmental rack in a forward direction to rotate the registering-wheel, means for returning the

rack to normal position, a stop arranged in the path of movement of the rack and means carried by each of the levers for moving the stop into position to prevent overthrow of the rack and means for locking the rack against return until it has completed its forward movement; substantially as described.

53. In a calculating-machine, the combination of a registering-wheel, means for actuating the registering-wheel, comprising a segmental rack and a lever for rocking the rack in a forward direction to rotate the registering-wheel, means for returning the rack to normal position, a toothed dog, an arm operated by the lever engaging the toothed dog during the forward movement of the rack and means also operated by the lever for releasing the arm from engagement with the toothed dog at the completion of the forward movement of the rack; substantially as described.

54. In a calculating-machine, the combination of a series of registering-wheels, separate means for actuating the several registering-wheels, each comprising a segmental rack, a lever arranged when operated to rock any one of the racks in a forward direction to rotate a registering-wheel, means for returning the rack to normal position, a toothed dog, an arm operated by the lever engaging the toothed dog during the forward movement of the rack and means also operated by the lever for releasing the arm from engagement with the toothed dog at the completion of the forward movement of the rack; substantially as described.

55. In a calculating-machine, the combination of a registering-wheel, means for actuating the registering-wheel, comprising a segmental rack, a series of levers each arranged, when operated, to rock the rack in a forward direction to rotate the registering-wheel, means for returning the rack to normal position, a toothed dog, an arm operated by each of the levers engaging the toothed dog during the forward movement of the rack and means also operated by each of the levers for releasing the arm from engagement with the toothed dog at the completion of the forward movement of the rack; substantially as described.

56. In a calculating-machine, the combination of a series of registering-wheels, separate means for actuating the several registering-wheels, each comprising a segmental rack, a series of levers, each arranged, when operated, to rock any one of the series of racks in a forward direction to rotate a registering-wheel, means for returning the rack to normal position, a toothed dog, an arm operated by each of the levers engaging the toothed dog during the forward movement of the rack and means also operated by each of the levers for releasing the arm from engagement with the toothed dog at the completion of the forward movement of the rack; substantially as described.

57. In a calculating-machine, the combination with a registering-wheel, means for actuating the registering-wheel, comprising a segmental rack, a lever arranged, when operated, to rock the rack in a forward direction and provided with a projection, means for returning the rack to normal position, a rocking plate carrying a stop-arm arranged in the plane of movement of the rack, an arm also carried by the rocking plate and having a cam-slot adapted to engage the projection on the lever; substantially as described.

58. In a calculating-machine, the combination with a series of registering-wheels, separate means for actuating the several registering-wheels, each comprising a segmental rack, a lever arranged, when operated, to rock any one of the racks in a forward direction and provided with a projection, means for returning the racks to normal position, a rocking plate carrying a series of stop-arms each arranged in the plane of movement of one of the racks, an arm also carried by the rocking plate and having a cam-slot adapted to engage the projection on the lever; substantially as described.

59. In a calculating-machine, the combination with a registering-wheel, means for actuating the registering-wheel, comprising a segmental rack, a series of levers each arranged, when operated, to rock the rack in a forward direction and each provided with a projection, means for returning the rack to normal position, a rocking plate carrying a stop-arm arranged in the plane of movement of the rack, a series of arms also carried by the rocking plate and each having a cam-slot adapted to engage the projection on one of the levers; substantially as described.

60. In a calculating-machine, the combination with a registering-wheel, means for actuating the registering-wheel, comprising a segmental rack, a lever arranged, when operated, to rock the rack in a forward direction, and provided with a projection, means for returning the rack to normal position, a toothed dog pivoted to the frame of the machine, a rocking plate carrying an arm adapted to be engaged by the teeth of the dog, a second arm also carried by the rocking plate and having a cam-slot adapted to engage the projection on the lever, and means operated by the rocking plate to release the arm from its engagement with the toothed dog on the completion of the forward movement of the rack; substantially as described.

61. In a calculating-machine, the combination with a series of registering-wheels, separate means for actuating the several registering-wheels, each comprising a segmental rack, a lever arranged, when operated, to rock any one of the racks in a forward direction, and provided with a projection, means for returning the racks to normal position, a toothed dog pivoted to the frame of the machine, a rocking plate carrying an arm adapted to be

engaged by the teeth of the dog, a second arm also carried by the rocking plate and having a cam-slot adapted to engage the projection on the lever, and means operated by the rocking plate to release the arm from its engagement with the toothed dog on the completion of the forward movement of the rack operated; substantially as described.

62. In a calculating-machine, the combination with a registering-wheel, means for actuating the registering-wheel, comprising a segmental rack, a series of levers each arranged, when operated, to rock the rack in a forward direction, and each provided with a projection, means for returning the rack to normal position, a toothed dog pivoted to the frame of the machine, a rocking plate carrying an arm adapted to be engaged by the teeth of the dog, a series of arms also carried by the rocking plate and each having a cam-slot adapted to engage the projection on one of the levers, and means operated by the rocking plate to release the arm from its engagement with the toothed dog on the completion of the forward movement of the rack; substantially as described.

63. In a calculating-machine, the combination of registering-wheels, representing different denominations, each of the registering-wheels being provided with a pinion and the registering-wheel of lower denomination being provided with a radial pin, and the registering-wheel of higher denomination being provided with a ratchet-wheel, separate means for actuating the registering-wheels, a double-armed carrying-pawl having on one arm a finger arranged in the path of the radial arm of the registering-wheel of lower denomination, and having on its other arm a pivoted pawl having a tooth engaging the ratchet-wheel of the registering-wheel of higher denomination, a fixed stop arranged to hold the pivoted pawl when depressed, in engagement with the ratchet-wheel to lock the registering-wheel of higher denomination against rotation in either direction, and means, operated by the mechanism for actuating the registering-wheel of higher denomination for lifting the pivoted pawl out of engagement with the stop; substantially as described.

64. In a calculating-machine, the combination of registering-wheels, representing different denominations, each of the registering-wheels being provided with a pinion and ratchet-wheel, detent-pawls engaging the ratchet-wheels, the registering-wheel of lower denomination being provided with a radial pin, and the registering-wheel of higher denomination being provided with a second ratchet-wheel, separate means for actuating the registering-wheels, a double-armed carrying-pawl having on one arm a finger arranged in the path of the radial arm of the registering-wheel of lower denomination, and having on its other arm a pivoted pawl having a tooth engaging the second ratchet-wheel of the reg-

istering-wheel of higher denomination, a fixed stop arranged to hold the pivoted pawl, when depressed, in engagement with the second ratchet-wheel to lock the registering-wheel of higher denomination against rotation in either direction, and means, operated by the mechanism for actuating the registering-wheel of higher denomination for lifting the pivoted pawl out of engagement with the stop; substantially as described.

65. In a calculating-machine, the combination of registering-wheels, representing different denominations, each of the registering-wheels being provided with a pinion, and a ratchet-wheel, detent-pawls engaging the ratchet-wheels, the registering-wheel of lower denomination being provided with a radial pin and having a portion of its periphery cut away to form a cam, and the registering-wheel of higher denomination being provided with a second ratchet-wheel, separate means for actuating the registering-wheels, a double-armed carrying-pawl having on one arm a finger arranged in the path of the radial arm of the registering-wheel of lower denomination, and a finger arranged to rest upon the cam formed on the periphery of the registering-wheel, and having on its other arm a pivoted pawl having a tooth engaging the ratchet-wheel of the registering-wheel of next higher denomination, a fixed stop arranged to hold the pivoted pawl when depressed in engagement with the second ratchet-wheel to lock the registering-wheel of higher denomination against rotation in either direction, and means, operated by the mechanism for actuating the registering-wheel of higher denomination for lifting the pivoted pawl out of engagement with the stop; substantially as described.

66. In a calculating-machine, the combination of registering-wheels representing different denominations, each of the registering-wheels being provided with a pinion and a ratchet-wheel, detent-pawls engaging the ratchet-wheels, the registering-wheel of lower denomination being provided with a radial pin, and the registering-wheel of higher denomination being provided with a second ratchet-wheel, separate means for actuating the registering-wheels, comprising a segmental rack adapted to engage the pinion but normally out of engagement therewith, a cam-plate connected with the rack and means for raising the cam-plate to raise the rack into engagement with the pinion, means for carrying from the registering-wheel of lower denomination to the registering-wheel of higher denomination, arranged to be actuated by the radial pin carried by the registering-wheel of lower denomination and provided with a pawl, having a tooth adapted to engage the second ratchet-wheel of the registering-wheel of higher denomination, a fixed stop against which the tooth of the pawl rests when depressed and by which the tooth is

caused to lock the ratchet-wheel against movement in either direction and means carried by the cam-plate of the actuating mechanism of the registering-wheel of higher denomination for lifting the pawl out of engagement with the fixed stop; substantially as described.

67. In a calculating-machine, the combination of registering-wheels representing different denominations, each of the registering-wheels being provided with a pinion and a ratchet-wheel, detent-pawls engaging the ratchet-wheels, the registering-wheel of lower denomination being provided with a radial pin, and the registering-wheel of higher denomination being provided with a second ratchet-wheel, separate means for actuating the registering-wheels, comprising a segmental rack adapted to engage the pinion but normally out of engagement therewith, a cam-plate connected with the rack and means for raising the cam-plate to raise the rack into engagement with the pinion, means for carrying from the registering-wheel of lower denomination to the registering-wheel of higher denomination, comprising a double-armed pawl having one arm arranged to be actuated by the radial pin carried by the registering-wheel of lower denomination and having its other arm provided with a pawl, having a tooth adapted to engage the second ratchet-wheel of the registering-wheel of higher denomination, a fixed stop against which the tooth of the pawl rests when depressed and by which the tooth is caused to lock the ratchet-wheel against movement in either direction and means carried by the cam-plate of the actuating mechanism of the registering-wheel of higher denomination for lifting the pawl out of engagement with the fixed stop; substantially as described.

68. In a calculating-machine, the combination of registering-wheels representing different denominations, each of the registering-wheels being provided with a pinion and a ratchet-wheel, detent-pawls engaging the ratchet-wheels, the registering-wheel of lower denomination being provided with a radial pin and having a cam formed therein, and the registering-wheel of higher denomination being provided with a second ratchet-wheel, separate means for actuating the registering-wheels, comprising a segmental rack adapted to engage the pinion but normally out of engagement therewith, a cam-plate connected with the rack and means for raising the cam-plate to raise the rack into engagement with the pinion, means for carrying from the registering-wheel of lower denomination to the registering-wheel of higher denomination, comprising a double-armed pawl having on one of its arms a finger arranged to be actuated by the radial pin carried by the registering-wheel of lower denomination, and a finger arranged to be actuated by the cam formed on the registering-wheel and having its other arm provided with a pawl, having a

tooth adapted to engage the second ratchet-wheel of the registering-wheel of higher denomination, a fixed stop against which the tooth of the pawl rests when depressed and 5 by which the tooth is caused to lock the ratchet-wheel against movement in either direction and means carried by the cam-plate of the actuating mechanism of the registering-wheel of higher denomination for lifting

the pawl out of engagement with the fixed stop; substantially as described.

In testimony whereof I affix my signature in presence of two witnesses.

JOHN T. HOWIESON.
